UNITED STATES PATENT OFFICE.

HALFDAN A. STEEN, OF MILWAUKEE, WISCONSIN, ASSIGNOR, BY MESNE ASSIGNMENTS, TO ALLIS-CHALMERS MANUFACTURING COMPANY, A CORPORATION OF DELAWARE.

OVERLOAD PROTECTIVE DEVICE.

1,206,157.

Specification of Letters Patent. Patented Nov. 28, 1916.

Application filed July 22, 1911. Serial No. 639,962.

To all whom it may concern:

Be it known that I, HALFDAN A. STEEN, a subject of the King of Norway, residing at Milwaukee, in the county of Milwaukee and State of Wisconsin, have invented certain new and useful Improvements in Overload Protective Devices, of which the following is a full, clear, and exact specification.

My invention relates to control devices, such as protective devices, of the overload or other type, for alternating current circuits, and more particularly to the adjustment of such devices. In the operation of devices of this character the adjustment has heretofore generally been obtained by varying the air gap of the device. This is often unsatisfactory, for many reasons.

It is the object of my present invention to eliminate this mechanical adjustment, and to provide an electrical adjustment instead. In attaining this object an additional coil is provided on the same magnetic circuit as the series coil of an overload protective or other device for alternating current circuits, and this additional coil is connected in a local circuit of variable resistance. This produces a current transformer, the main series coil being the primary and the additional coil the secondary. By varying the resistance of the secondary circuit of this transformer, the flux produced by the passage of a given current through the primary is also varied. In consequence, the value of the current at which the device operates may be varied by adjusting the resistance of the circuit of the additional coil.

The various novel features of my invention will appear from the description and drawings, and will be particularly pointed out in the claims.

Figure 1 shows diagrammatically one embodiment of my invention; and Fig. 2 shows a modification.

The alternating current device to be protected, here shown as an alternating current generator 10, is connected to the alternating current circuit 11 through a circuit-breaker 12, this circuit-breaker being biased to open position but normally held in closed position by a latch 13. A coil 14 is connected so as to carry a current proportional to the current supplied by the generator 10; as shown, the coil 14 is in series with such generator. The core 15 of the overload coil 14 may act

directly on the latch 13 of the circuit-breaker, as shown in Fig. 1, or may control a switch 16 in the circuit of a coil 17 controlling such latch, as shown in Fig. 2. The coil 17 is shown as a tripping coil and the switch 16 as normally open.

On the same magnetic circuit as the coil 14 is an additional coil 18. The coils 14 and 18 are preferably so wound relatively to each other that the magnetic leakage between the coils is as small as possible. This is indicated on the drawings by the superposition of one coil upon the other. The coil 18 is connected in a local circuit in which is a variable impedance 19; this impedance is illustrated as a simple rheostat.

The coils 14 and 18, with their common core 15, form a current transformer. For a given current in the primary of such a transformer, the current in the secondary remains substantially constant regardless of the resistance of the secondary circuit. The effect of a variation in the resistance of the secondary circuit, the primary current remaining constant, is thus to vary in the same sense as such resistance variation the voltages across the terminals of the respective transformer coils and the flux in the transformer core. Thus for a given current in the machine 10, a variation in the value of the resistance 19 produces a variation in the same sense in the flux produced in the core 15. Since the core 15 will be raised when traversed by a given flux, and will thereupon either actuate the latch 13 directly or close the switch 16 and cause such actuation by the tripping coil 17, a variation in the value of the resistance 19 will vary the value of the current at which the circuit-breaker 12 is tripped. The greater the amount of the resistance 19 in circuit with the coil 18 the lower will be the ampere point of operation of the circuit-breaker. Thus an easy and accurate mode of adjustment is provided.

My invention is capable of wide modification in detail, and I aim to cover every such modification which does not depart from the spirit and scope of my invention as set forth in the appended claims.

What I claim as new is:

1. In an automatic circuit-breaking device for alternating current circuits, an

electromagnet comprising a winding carrying alternating current, an element of magnetic material disposed in inductive relation to said winding and movable in response to 5 energization of said winding to a predetermined degree, a circuit-controlling device rendered operative through actuation of said element of magnetic material, and means for varying the value of current in 10 said winding at which said element of magnetic material is actuated for circuit-controlling purposes, said means comprising a second winding permanently closed-circuited and in inductive relation to said first winding and said element of magnetic material, and a variable impedance in the circuit of 15 said second winding.

2. In a circuit-breaking apparatus for alternating current circuits, controlling 20 means responsive to abnormal conditions in the circuit to be controlled and comprising a winding carrying alternating current proportional to the current in the circuit to be controlled, a movable member of magnetic 25 material whose effective actuation is controlled by magnetic effects produced thereon by said winding, and means for varying the value of current in said winding at which said member is effectively actuated, said latter means comprising a winding inductively 30 related to said first winding and said member of magnetic material and permanently closed-circuited through a variable impedance during the use of the apparatus.

3. In a circuit-controlling apparatus, a switch, and means for controlling the operation of said switch in response to abnormal conditions in the circuit to be controlled, said controlling means comprising an operating coil carrying alternating current of an 40 intensity proportional to that of the current in the circuit to be controlled, a member of magnetic material inductively related to said coil and actuatable in response to sufficient energization of said coil, and means for 45 modifying the effect of said coil on said member of magnetic material to variably adjust the value of current in said coil at which said member is effectively actuated, 50 said means comprising a second coil inductively related to said first coil and said member of magnetic material and permanently closed-circuited through a variable resistance.

4. In a circuit-controlling apparatus for alternating current circuits, a controlling device responsive to abnormal conditions in the circuit to be controlled, said controlling device comprising an operating coil carrying 60 alternating current proportional to the

current in the circuit to be controlled, and a member of magnetic material movable under the influence of the magnetic effects produced thereon by said coil, and means for calibrating said controlling device for rendering the latter capable of effectively actuating said member of magnetic material on the occurrence of abnormal circuit conditions of different intensities, said calibrating means comprising a short-circuited coil inductively related to said first coil and said member of magnetic material, and a variable impedance in the circuit of said second coil, 65 70

5. In a circuit-controlling apparatus, a controlling device responsive to abnormal conditions of different intensities in the circuit to be controlled, said controlling device comprising an operating winding carrying alternating current of a value proportional to that of the current in the circuit to be controlled, and a member of magnetic material actuatable under the influence of the magnetic effects produced thereon by said winding, and means for calibrating said controlling device to render said device capable of 85 effectively actuating said member of magnetic material on the occurrence of abnormal circuit conditions of different intensities, said calibrating means comprising a short-circuited winding inductively related to said first winding and said member of magnetic material, and regulable means associated with said second winding and operative to 90 vary the effect of said second winding in opposing actuation of said member of magnetic material by said first winding, 95

6. In an automatic circuit-controlling device for alternating current circuits, an electromagnet comprising a winding, and an element of magnetic material inductively 100 related to said winding and movable in response to energization of said winding to a predetermined degree, a controlling member rendered operative through actuation of said element of magnetic material, and 105 means for varying the value of alternating current in said winding at which said element of magnetic material is actuated for effective circuit-controlling purposes, said means comprising a second winding inductively related to said first winding and said element of magnetic material and having its 110 circuit of variable impedance and closed during the use of the apparatus.

In testimony whereof I affix my signature, 115 in the presence of two witnesses.

HALFDAN A. STEEN.
